UNITED STATES PATENT OFFICE.

WILLIAM C. COLEMAN, OF WICHITA, KANSAS.

VIBRATORY SEPARATOR.

Application filed September 15, 1924. Serial No. 737,861.

To all whom it may concern:

Be it known that I, WILLIAM C. COLEMAN, a citizen of the United States, residing at Wichita, in the county of Sedgwick and State of Kansas, have invented certain new and useful Improvements in Vibratory Separators; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to separators for separating precious metal from ore pulp and the primary object is to provide an efficient means for recovering the precious metal from the ore. It is shown as comprising a vibratory rotor in which are arranged amalgamator plates radially disposed about a common center and a mercury chamber for recovering the precious metal and means is provided for regulating the rate of discharge of the pulp or sand to regulate the flow through the machine.

Jetting devices are provided for carrying off the sand without carrying off the precious metal and the invention consists in certain novel parts and combinations of parts, all of which will be specifically referred to hereinafter, reference being had to the accompanying drawings, in which—

Fig. 1 is a vertical, longitudinal, sectional view through a machine constructed in accordance with my invention, the vibratory mechanism being shown in elevation, and

Fig. 2 is a diagrammatic plan view showing the jetting nozzles.

The device is shown as comprising a rotor consisting of a vertical shell or drum 1 having an open ended cap or cover 2 and a bottom structure 3. The drum or cylindrical wall 1 is provided at its upper end with a ring 4, angular in cross section and within the drum is a ring 5, the two being bolted together by bolts 6 which pass through both rings and through the wall 1.

Resting upon the angular ring 4 is a horizontal disk 7 having perforations 8 near its periphery, the ring 4, the disk 7 and the cover 2 being fastened together by bolts 9. The disk 7 has a central collar 10 which is threaded on a collar 11 carried by the central conduit or tube 12.

The outer portion of the collar 10 re-

ceives a collar 13 which is part of a tube 14 passing through the cam disk 15 on the support 16. The tube 14 carries a cam 16 cooperating with the cam faces 17 on the cam disk 15 and the tube is rotated by suitable means as for example by a belt passing around the pulley 18 fast on tube 14.

The tubes 12 and 14 constitute a hollow shaft or conduit centrally of the machine through which water may be distributed to the radial conduits 20 which are fastened to the manifold 21 at the bottom of the tube 12. The tubes 20 discharge into an annular chamber 22 in the bottom member 3. The chamber 22 communicates with a plurality of jets or nozzles 23 arranged in circular series about the ring 24 constituting part of the bottom member 3.

The outer wall 25 of the bottom member 3 extends upwardly beyond the jets and it is spaced from the ring 24 to provide a mercury chamber 26. There is a horizontal flange 27 connected to the ring 24 and extending over the mercury chamber 26 adjacent to the outlet for the jets and the outer wall 25 of the bottom member 3 carries an angular cover 28 having an inwardly and upwardly extending conical flange 29 which is substantially parallel with the downwardly and outwardly disposed conical flange 30 carried by the wall so that a tortuous passageway is provided for the sand admitted through the open cover 2. The bottom member is in spaced relation with the wall 1 but it is secured thereto by the strips 31 which are fastened to the wall 1 and to the member 28 by bolts 32 which also secure the bottom cover plate 33 to the bottom member.

The mercury chamber may be provided with a pipe or pipes 34 if desired. Within the chamber surrounded by the wall 1 are a plurality of amalgamator plates 35 arranged radially about the pipe 12, the inner edges of the plates 35 being spaced from the pipe 12 and the spaces between the plates are in line with the openings or perforations 8 so that pulp which is admitted into the open ended cover 2 may be distributed by the disk 7 into the spaces between the amalgamator plates so the amalgamator plates may separate out some of the precious metal. The plates are clamped between two rings 36 and 37 by bolts 38, the upper ring 36 having fingers 39 which rest upon the ring 5.

The space within the wall 1 is the amalgamator space as distinct from the mercury chamber 26 and as ore pulp is fed into the cover 2, the rotary action of the machine 5 will cause the pulp to move, due to centrifugal force to the perforations 8 and flow down through the amalgamator plates 35 onto the valve plate 40, carried by the conduit 12 and adjustable vertically by the adjusting 10 nut 41 threaded on pipe 12.

The ring 24 has an upwardly and outwardly inclined face 42 adjacent to the periphery of the valve or gate 40. The periphery of the valve or gate 40 is in spaced 15 relation with the wall 24 so by adjusting the member 40 vertically, the space between it and the ring 24 will be varied to vary the rate of discharge from the mercury chamber. The ore pulp will tend to pack 20 at this point but this can be relieved by flowing water through the conduit consisting of the pipes 12 and 14 through the radial conduits 20, through chamber 22 and jets 23 so that the sand which tends to pack 25 will be forced out through the space between the rings 29 and 30, any precious metal in the sand at this point being carried over into the mercury chamber 26. The major portion of the sand of course will flow out 30 through the space between the valve 40 and the ring 24 since the bottom member 3 is annular and has a large central opening.

While the machine is rotating the cam 16 will ride over the cam faces 17 of the cam 35 disk 15, these cams being in the form of sinusoidal curves to cause a vertical vibratory motion as the rotor rotates. Whenever the sand tends to pack at the bottom 40 of the machine, whether it is in a state of rest or rotating, the water can be admitted through the central conduit to wash it away and by providing a slow rate of feed of the ore pulp through the machine, the amalgamator plates will have ample opportunity to attract most of the precious metal, 45 practically all of the remaining being received in the mercury chamber.

It is to be understood of course that as the machine rotates, the mercury will 50 climb up to the top of the wall 25 so that as the sand is washed out through the space between the flanges 29 and 30 it will pass over the mercury giving the mercury an opportunity to absorb the precious metal. 55 I prefer to construct the tubes or conduits 20 of flexible material such as hose and fasten them in place by clamps or similar fastening devices 43. The purpose of using hose is for ease of assembly but I do not wish 60 to be limited to the use of flexible conduits in all constructions of my invention.

It will be apparent from the foregoing 65 that the ore pulp can be introduced into the top of the machine from the distributor disk 7 where it will be distributed between

the amalgamator plates 35 and since these have considerable area, being longitudinally and radially disposed within a relatively deep drum and that there will be considerable surface area over which the ore pulp 70 passes as it gravitates to the bottom of the machine and that any metal which the radial, longitudinally disposed amalgamator plates does not attract will be recovered by the mercury in the mercury chamber 26. 75 The vibratory action communicated to the machine will cause agitation of the ore pulp as it passes therethrough which will prevent the ore pulp from stratifying and thereby give the amalgamator plates an opportunity 80 to act on all of the sand.

What I claim and desire to secure by Letters-Patent is:

1. A separator comprising a rotatable 85 vertically disposed member open at its respective ends, a bottom member connected to the first named member provided with a mercury compartment, radial amalgamator plates in the first member, a distributor above the amalgamator plates for distributing material into the spaces between the amalgamator plates so that it may gravitate to the bottom member, a valve member on to which the material may be deposited, the valve member being within the bottom member and having its periphery spaced from the bottom member, the bottom member being spaced from the first named member, water jets adjacent to the periphery of the first named member at its lower edge, said jets being supported by the bottom member and means for delivering water to the jets. 95

2. A separator comprising a rotatable 105 vertically disposed member open at its respective ends, a bottom member connected to the first named member provided with a mercury compartment, radial amalgamator plates in the first member, a distributor above the amalgamator plates for distributing 110 material into the spaces between the amalgamator plates so that it may gravitate to the bottom member, a valve member on to which the material may be deposited, the valve member being within the bottom member and having its periphery spaced from the bottom member, the bottom member being spaced from the first named member, water jets adjacent to the periphery of the first named member at its lower edge, and adjacent to the mercury compartment in 115 the bottom member. 120

3. A separator comprising a rotatable 125 vertically disposed member open at its respective ends, a bottom member connected to the first named member provided with a mercury compartment, radial amalgamator plates in the first member, a distributor above the amalgamator plates for distributing material into the spaces between the amalgamator plates so that it may gravitate 130

to the bottom member, a valve member on to which the material may be deposited, the valve member being within the bottom member and having its periphery spaced 5 from the bottom member, the bottom member being spaced from the first named member, water jets adjacent to the periphery of the first named member at its lower edge, said jets being supported by the bottom 10 member and means for delivering water to the jets, and means for vertically vibrating the first and second mentioned members in synchronism during the rotation thereof.

4. A separator comprising a rotatable 15 vertically disposed member open at its respective ends, a bottom member connected to the first named member provided with a mercury compartment, radial amalgamator plates in the first member, a distributor 20 above the amalgamator plates for distributing material into the spaces between the amalgamator plates so that it may gravitate to the bottom member, a valve member being within the bottom member and having its periphery spaced from the bottom member, the bottom member being spaced from the first named member, water jets adjacent to the periphery of the first named member at its 25 lower edge and adjacent to the mercury compartment in the bottom member, and means for vertically vibrating the first and second mentioned members in synchronism during the rotation thereof.

5. A separator comprising a vertical 30 drum and a ring-shaped bottom member secured thereto in spaced relation, radial amalgamator plates in the drum, a distributor above the amalgamator plates, a mercury chamber in the bottom member, jetting devices adjacent to the mercury chamber, means for supplying water to the jetting devices and an adjustable valve within the bottom member having a diameter substantially co-extensive with the diameter of the drum.

6. A separator comprising a vertical 35 drum and a ring-shaped bottom member secured thereto in spaced relation, radial amalgamator plates in the drum, a distributor above the amalgamator plates, a mercury chamber in the bottom member, jetting devices adjacent to the mercury chamber, means for supplying water to the jetting devices and an adjustable valve within the bottom member having a diameter substantially co-extensive with the diameter of the drum, said valve comprising a disk 40 axially supported within the bottom member.

7. A separator comprising a vertical 45 rotatable drum having an inlet at its top and an outlet at its bottom, amalgamator plates in the drum, a ring shaped bottom member connected to the drum having a

mercury chamber, a valve in spaced relation with the bottom of the drum having a diameter substantially co-extensive with the diameter of the drum but spaced therefrom so as to provide an outlet space between the valve and the drum and jetting devices in the ring-shaped member adjacent to the mercury chamber.

8. A separator comprising a vertically disposed rotatable drum open at its respective ends, the upper end being the inlet opening and the lower end the discharge opening, a ring-shaped member suspended from the lower portion of the drum in spaced relation thereto, jetting devices carried by the member and discharging adjacent to the space between the bottom member and the drum and a disk supported within the bottom member and having an edge spaced from the bottom member and from the drum.

9. A separator comprising a rotatable drum, vertically disposed radial amalgamator plates in the drum grouped about a common center space, means for feeding the material into the space between the amalgamator plates, a ring-shaped member suspended in spaced relation from the bottom of the drum, the bottom of the drum and ring-shaped member having spaced overlapping flanges and jetting devices adjacent to the flanges and a disk supported axially of the drum and bottom member in spaced relation with both upon which material may be gravitated from the drum.

10. A separator comprising a rotatable drum, vertically disposed radial amalgamator plates in the drum grouped about a common center space, means for feeding the material into the space between the amalgamator plates, a ring-shaped member suspended in spaced relation from the bottom of the drum, the bottom of the drum and ring-shaped member having spaced overlapping flanges and jetting devices adjacent to the flanges and a disk supported axially of the drum and bottom member in spaced relation with both upon which material may be gravitated from the drum, the ring-shaped member having an inner outwardly inclined wall and means for adjusting the disk.

11. A separator comprising a vertical drum, means for rotating the drum, the drum having an inlet at its top, a distributor in the top of the drum, amalgamator plates in the drum, a disk supported below the open bottom of the drum, a ring-shaped bottom member surrounding the disk having an annular mercury chamber, a lateral flange carried by the bottom member extending over a portion of the mercury chamber and spaced overlapping flanges on the lower edge of the drum and on the bottom member.

4

12. A separator comprising a vertical drum, means for rotating the drum, the drum having an inlet at its top, a distributor in the top of the drum, amalgamator plates in the drum, a disk supported below the open bottom of the drum, a ring-shaped bottom member surrounding the disk having an annular mercury chamber, a lateral flange carried by the bottom member ex-

tending over a portion of the mercury 10 chamber and spaced overlapping flanges on the lower edge of the drum and on the bottom member, and jetting devices adjacent to the flanges.

In testimony whereof I affix my signature.

WILLIAM C. COLEMAN.
